UNITED STATES PATENT OFFICE.

JOHN LINDSAY, OF SAN FRANCISCO, CALIFORNIA.

CASEMENT WINDOW.

Application filed May 9, 1927. Serial No. 189,981.

My invention relates to improvements in casement windows having one or more sashes, and it consists in the combinations, constructions and arrangements hereinafter described 5 and claimed.

An object of my invention is to provide a casement window which is constructed so as to be hung with the minimum amount of work and which has means for supporting 10 itself in the window frame for permitting the carpenter to use both hands in securing the device to the window frame and for adjusting the sash with respect to the frame.

A further object of my invention is to provide a device of the type described which may 15 be removed for repairs, or the like, by merely unscrewing two screws.

A further object of my invention is to provide a device of the type described which is 20 extremely simple in construction and which slight adjustments between the sash and window frame may be made without the necessity of removing and resetting any of the screws which connect the sash to the frame.

Other objects and advantages will appear 25 in the following specification, and the novel features of my invention will be particularly pointed out in the appended claims.

My invention is illustrated in the accompanying drawing forming a part of this application, in which

Figure 1 is a front elevation of the device, a portion of the frame being broken away for illustrating certain of the mechanism.

Figure 2 is a section along the line 2—2 of Figure 1;

Figure 3 is a section along the line 3—3 of Figure 1;

Figure 4 is a perspective view of a shoe 40 used in the device;

Figure 5 is a perspective view of the novel link construction; and

Figure 6 is a section along the line 6—6 of Figure 5.

In carrying out my invention I provide a casement frame 1 and in the bottom rail 2 and top rail 3 I mount guide members 4 of the shape shown in Figure 4. These members are secured in place by any means, such as screws, 50 or the like and extend parallel with the plane of the window.

Upon each guide member 4 I mount a shoe 5 of the shape shown in Figure 4. This shoe is movable along the member 4 and carries a pivot rod 6 which is adapted to project up 55 into a sash 7 as shown in Figure 2. The sash

7, of course, is provided with bores for receiving the rods or pins 6.

Before the sash 7 is disposed in place, the shoes 5 may be moved with respect to each other so that the sash 7 may be pivotally secured to the lower shoe first and then be tilted at an angle so as to align pin 6 carried by the upper shoe with the opening in the upper part of the sash. The sash may then be swung 60 into vertical position, thus aligning the shoes 5 vertically and causing the shoes to pivotally support the sash. The sash carries bearing plates 8, see Figure 4, which are secured to the sash by screws, not shown, passed through 65 openings 9. The plates 8 have openings 10 for receiving the pins 6. This construction prevents the openings in the sash from becoming enlarged through wear.

Before the sash 7 has been hung in place 75 the links 11 are secured to the sash by fastening pivot plates 12 to the sash. The position of the plates 12 on the sash 7 may be determined without measuring any part of the window frame itself. In locating the plates 80 12 in their proper positions, the links 11 are laid upon the sash so that the brackets 13 coincide with the edge 14 of the sash 7. The plates 12 may now be secured to the sash 7 in the position they will assume after the 85 brackets 13 have aligned with the edge 14 in the manner just described. It should be noted that the plates 12 may be secured to the sash prior to the time that the sash is hung between the shoes 5, or after.

One of the principal features of the invention lies in the fact that the links 11 may be secured to the frame 1, while the sash 7 is pivotally supported and without the need of the carpenter holding the sash with one hand and 95 securing the brackets 13 to the frame 1 with the other. The carpenter merely places the brackets 13 in the position shown in Figure 3 and secures the brackets in place by means of screws 15.

From the foregoing description of the various parts of the device, the operation thereof may be readily understood.

Figure 3 shows the sash 7 partially open, which is the approximate position the sash 105 will assume while the brackets 13 are being secured in place. Assume that the sash is not in its proper position with respect to frame 1 so that there will be a slight binding between the frame and the sash when the sash 110 is closed. In this instance a set screw 16, see Figure 5, may be loosened from a keeper plate

17 for permitting the plate to be moved with respect to the bracket 13, thus moving the pivot point between the link 11 and the bracket without the necessity of removing the screws 15. Figure 3 clearly shows how the screw 16 may be moved in the slot 18 and then be tightened to the keeper plate 17 after adjustment. With the standard type of casement window it is necessary to remove approximately ten screws in order to adjust the sash within a frame and the openings made by the screws have to be plugged before the screws are again inserted into the frame in their new positions. Of course, the second adjustment of the sash in the standard window frame is not so firmly mounted as the first. This disadvantage is overcome with the present construction because the adjustment of the sash 7 may be accomplished by moving the screw 16 in the slot 18. The keeper plate 17 has a threaded opening for the screw 16 and acts as a nut for receiving a screw. Figure 5 clearly shows how the plate has upwardly turned flanges 18 which bear against the edges of the bracket 13 for guiding the keeper plate along the bracket. The sectional view in Figure 2 further shows how the sash 7 is provided with a lip 20 at the top and bottom thereof for covering the shoes 5 and the guide members 4.

In Figure 2 I show a slight space between the sash 7 and the window sill and also a slight space between the bottom of the lip 20 and the window frame. It is well known that windows sweat and that the moisture collects in drops and flows down on the inside of the window sash. This moisture usually collects between the sash and the window sill and of course in time rots away the wood at this point. With my device the member 4 acts as a water strip in that it guides the condensed water vapor from the inside of the window frame to the outside thereof. Water collecting on the metal parts will not rot the wood away when flowing from these parts over the bottom of the window sill because there will be a complete drain for the water. In this way the window frame is preserved and will have a much longer life than will the standard window.

Oftentimes it becomes necessary to remove the sash 7 either for repair work or for other purposes and to do this it is merely necessary to remove the screws 16, which frees the links 11 from the window frame and permits the sash to be removed from the pins 6 by inclining the pivotal edge of the sash at a slight

angle so as to permit the pins to be removed from their places in the sash. The sash can again be hung in the frame and is secured in place by again tightening the set screws 16 which secure the links to the bracket 13.

In Figure 4 I show the shoe 5 as being provided with a leaf spring 5' of the shape shown. This spring bears against the vertical portion of the members 4 and has its ends bent around the ends of the shoe 5. The spring is disposed between the shoe and the member 4 and creates enough frictional pressure upon the member to hold the shoe in adjusted position with respect to the member. Still a further feature from the present construction lies in the fact that the links 11 may be made of heavier material and of longer lengths for larger windows, so that they will be able to withstand the strain to which larger windows are subjected.

With the standard casement window the links are intimately connected with the other parts of the window frame so that the same size links will be used for windows having a small area as well as windows having a large area. This, of course, should not be the case, because it places an undue strain upon the links when they are attached to sashes having a larger area.

Although I have shown and described one embodiment of my invention, it is to be understood that the same is susceptible of various changes and I reserve the right to employ such changes as may come within the scope of the appended claims.

I claim:

1. In a device of the type described, a casement, a sash pivotally mounted in said casement, links connecting said sash with said casement, the means connecting said links to said casement including metal brackets permanently secured to the casement and having slots therein and bolts for securing said links to said brackets in adjusted position.

2. A casement window comprising a frame, guide rails disposed at the bottom and at the top of said frame, shoes slidable on said rails and carrying pins, and a sash having aligned openings extending parallel with and disposed adjacent to one of its vertical edges for receiving said pins, said pins being of such a length as to permit the rails and shoes to be first secured in place and then the sash mounted on one pin and then tilted at its opposite end for permitting it to receive the other pin.

JOHN LINDSAY.
